Primary Examiner — Deanna L Pratt*Assistant Examiner* — Natasha Vujcic(74) *Attorney, Agent, or Firm* — Manabu Kanesaka(57) **CLAIM**

The ornamental design for a hole plug, as shown and described.

DESCRIPTION

FIG. 1 is a perspective view from the plan side of a hole plug showing my new design;

FIG. 2 is a perspective view from the bottom side thereof;

FIG. 3 is a plan view thereof;

FIG. 4 is a bottom view thereof;

FIG. 5 is a front view thereof; a rear view being symmetrical to the front view;

FIG. 6 is a right side view thereof;

FIG. 7 is a left side view thereof;

FIG. 8 is a cross-sectional view thereof along the line 8-8 in FIG. 3;

FIG. 9 is a cross-sectional view thereof along the line 9-9 in FIG. 3;

FIG. 10 is a cross-sectional view thereof along the line 10-10 in FIG. 3;

FIG. 11 is a cross-sectional view thereof along the line 11-11 in FIG. 3; and,

FIG. 12 is a cross-sectional view thereof along the line 12-12 in FIG. 3.
